[57] CLAIM

The ornamental design for a cannula reel, as shown and described.

DESCRIPTION

FIG. 1 is a front elevational view of the cannula reel showing our new design;

FIG. 2 is a rear elevational view thereof;

FIG. 3 is a right view thereof;

FIG. 4 is a left view thereof;

FIG. 5 is a top plan view thereof; and,

FIG. 6 is a bottom plan view thereof.

In FIGS. 1 through 6, the oxygen tubing is shown broken away to indicate indeterminate length.
